UNITED STATES PATENT OFFICE.

ALFONSO D. GATES, OF CINCINNATI, OHIO.

HORSE-DETACHER.

SPECIFICATION forming part of Letters Patent No. 247,492, dated September 27, 1881.

Application filed January 28, 1881. (No model.)

To all whom it may concern:

Be it known that I, ALFONSO D. GATES, of Cincinnati, Hamilton county, Ohio, have invented certain new and useful Improvements 5 in Single-Trees, of which the following is a specification.

My invention comprises a metallic single-tree whose peculiar construction enables the ready and secure application thereto of a pair of 10 spring-bolts or their equivalents, which latter, when retracted, automatically disengage the traces from the vehicle. This result is accomplished by making the central portion or web of the single-tree flat, with considerable lateral 15 or horizontal spread, so as to afford the necessary strength of metal, and from this central web, which is perforated to admit the pivot or pin, the single-tree is developed into two concave or semi-tubular prolongations having an 20 inverted gutter shape. These concave extensions have housed within them the bolts or catches and the springs that cause their protrusion, while the central web is traversed by the pivot wherewith the single-tree is coupled 25 to the splinter-bar of the vehicle. Furthermore, these tubular prolongations are slotted longitudinally to permit the free passage of straps, or cords, or chains, or other flexible couplings 30 that connect the spring-bolts with the pivot, in order that a proper rotation of the latter may draw said bolts back within their respective 35 housings.

My invention further comprises a novel combination of notches and detents for maintaining 40 said bolts in their retracted positions, as hereinafter more fully described.

In the annexed drawings, Figure 1 is a plan of the under side of my metallic single-tree, the 45 spring-bolts and their accessories being omitted. Fig. 2 is a side elevation of the same. Fig. 3 is a vertical section of one-half of the single-tree. Fig. 4 is a plan of the other half of the single-tree, the extreme end of the same being sectioned. Fig. 5 is an enlarged transverse section of the device, taken in the plane of one of the retaining-notches.

My single-tree, which may be made either of cast or wrought metal, consists, essentially, of a central web, A, and two opposite prolongations, B C, which latter may be of any suitable 50 length. I prefer to make the central member,

A, flat, or nearly so, and give it considerable horizontal spread, as compared with the rest of the single-tree, in order that it may have sufficient strength of metal after the pivot-hole a 55 has been drilled through said web. Furthermore, this web can be made relatively thicker than the other portions of the device, as shown in Fig. 3. As the metal is developed to form the prolongations or extensions B C, the single-tree gradually assumes a concave or semi-tubular shape as it extends away from the web A, the greater portion of said prolongations being, 60 approximately, of the shape of an inverted gutter, as more clearly shown in Fig. 5. Extending from the web A a sufficient distance along these concave prolongations B C are slots b c, whose duties will presently appear. The ends of these semi-tubes are closed, except where openings b' c' are made for the passage of the 65 spring-bolts, and said ends have cast with them hooked-shaped keepers B' C', which latter serve to prevent the traces slipping off of the spring-bolts D E. These bolts are housed, respectively, within the concave prolongations B 70 C, and have at their inner ends eyes or rings or other means of attachment for cords or straps or their equivalent couplings d e, that connect said bolts with radial arms or loops f f' of a pin, F, wherewith the single-tree is pivoted to the splinter-bar G. Pivot F has a lever, H, to whose free end a strap or rod may be attached and then be carried back to the vehicle, 75 so as to give the driver instant control of said pivot. Lever H is preferably bent, as shown 80 in Fig. 4.

Surrounding bolt D is a helical spring, I, the outer end of which is passed transversely through said bolt, as seen in Fig. 5, while its inner end is fastened to the bearing or box J, 90 as represented in Fig. 3. This spring is so coiled and arranged as to advance the bolt and impart a slight rotation to the same when it is retracted.

Projecting laterally from the bolt D is a stop 95 or detent, K, adapted to snap into a notch or cavity, k, on the lower edge of the prolongation B, and either at the front or rear of the same, the free end of said stop being so shaped as to be readily depressed with the finger. The other 100 bolt, E, has a precisely similar arrangement of spring I', bearing J', stop K', and notch k'.

When the bolts D E are retracted their respective springs I I' insure such a rotation of said bolts as to cause the detents K K' to snap into the appropriate notches k k', and thereby retain the devices D E in their concealed positions.

To hitch the horse to the vehicle one of the trace-loops is first brought opposite the orifice b' in the end of the single-tree, and the stop K 10 is then depressed, which act causes the bolt D to fly out and enter said loop. The other trace-loop is then hitched to the opposite end of the single-tree in a similar manner, the keepers B' C' effectually preventing any accidental disengagement of said loops from their respective spring-bolts. When the bolts are thus protruded the tension on the flexible couplings d 15 e turns the pivot F so as to present its loops or arms f' f' longitudinally of the single-tree, as seen in Fig. 3; consequently the moment this pivot is turned so as to present said arms transversely of the single-tree, as seen in Fig. 4, the bolts D E are simultaneously retracted and the trace-loops dropped from the keepers 20 B' C', thus instantly unhitching the horse, and without compelling the driver to leave his seat in the vehicle.

As all the operative parts of my hitching appliances are housed within the concave extensions B C, it is evident the bolts and springs are protected from the inclemencies of the weather and are not liable to become injured, and yet can be readily inspected and oiled at any time from the under or open side of the 25 single-tree. Furthermore, this concave or semi-tubular single-tree combines the maximum of strength with the minimum of material, and presents a neat and shapely appearance, which

can be enhanced either by nickel-plating or japanning the device. Finally, the arms f' f' can be omitted, and cams or disks may be used for operating the cords, chains, or other flexible couplings d e.

I claim as my invention—

1. A metallic single-tree having a central web, A, and two concave or semi-tubular extensions, B C, all made of one piece of material, as set forth.

2. A single-tree having a central web, A, two concave prolongations, B C, and keepers 50 B' C', all made of one piece of metal, as herein described.

3. A metallic single-tree consisting of a central web, A, two slotted concave prolongations, B b, C c, and keepers B' C', all made of one 55 piece of material, as herein set forth.

4. The combination, in a single-tree, of sliding bolt D, spring I, stop K, and notch k, as herein described and set forth.

5. An improved single-tree consisting of the 60 central web, A a, slotted concave extensions B b, C c, keepers B' C', spring-bolts D I E I', couplings d e, pivot F f' f', lever H, stops K K', and notches k k', as herein set forth.

6. The spring I, coiled around the bolt D, 65 and having one of its ends attached thereto, while its other end is secured to the bearing J, so as to partially rotate said bolt when it is retracted, for the purpose stated.

In testimony of which invention I hereunto 70 set my hand.

ALFONSO D. GATES.
